UNITED STATES PATENT OFFICE.

CHARLES F. KADE, OF SHEBOYGAN, WISCONSIN.

FLUID CONTAINER OR RECEPTACLE.

SPECIFICATION forming part of Letters Patent No. 718,357, dated January 13, 1903.

Application filed November 29, 1902. Serial No. 133,254. (No model.)

To all whom it may concern:

Be it known that I, CHARLES F. KADE, a citizen of the United States, residing at Sheboygan, in the county of Sheboygan and State 5 of Wisconsin, have invented new and useful Improvements in Fluid Containers or Receptacles, of which the following is a specification.

This invention relates to fluid containers 10 or receptacles; and the primary object of the same is to provide a device of this class formed of glass, porcelain, or other suitable material in which retail fluids, such as inks, extracts, &c., are disposed and to be adapted 15 to serve some useful purpose after the fluid has been exhausted. It can be used as an ink-well and after the latter fluid has been exhausted can be readily cleaned, filled with salt, and turned upside down and arranged 20 for service as a salt cellar or shaker. This is only one instance of the many fluids that may be primarily disposed in the improved device; and the invention consists in the construction and arrangement of the several 25 parts, which will be more fully hereinafter described and claimed.

In the drawings, Figure 1 is a perspective view of a container or receptacle embodying the features of the invention and disposed, 30 for instance, as an ink-well. Fig. 2 is a transverse vertical section of the improved container or receptacle as shown arranged by Fig. 1. Fig. 3 is a view similar to Fig. 2 of the improved device inverted and ready 35 for use as a salt-shaker or other analogous device after the primary liquid has been exhausted therefrom.

Similar numerals of reference are employed 40 to indicate corresponding parts in the several views.

The numeral 1 designates a hollow body, which is shown substantially spherical in form and at one end has a dished or cup-shaped extremity 2, with an opening 3 centrally formed therein and communicating 45 with the interior of the body. The opposite extremity 4 is formed with a foraminous closure 5, located inwardly from a surrounding or circumferential terminal rib 6, and on the 50 exterior of said extremity, close to the location of the closure, a series of screw corruga-

tions 7 are provided for the removable attachment of a flanged cap 8, also formed with similar corrugations 9. In the opening 3 a stopper or closure 10 is removably mounted 55 to render the primary contents of the container or receptacle accessible and in the afteruse of the improved device to provide convenient means for filling the body 1 with salt or other material. 60

The shape or contour of the device may be varied without sacrificing the features of the invention, and the material used will be of a nature capable of resisting corrosion. It is also proposed to exteriorly ornament the body 65 by means of suitable designs burned therein or standing out in relief thereon. Between the cap 8 and the foraminous closure 5 in the primary preparation of the improved device a cork strip or disk 11 will be interposed to 70 prevent leakage of the liquid; but after the latter has been exhausted and the container or receptacle arranged for use as a salt-shaker or analogous device the cap 8 and cork strip or disk 11 are removed, as clearly 75 shown by Fig. 3. Both extremities of the improved device have a diametrical extent sufficient to provide a stable support for the container or receptacle when disposed on either end, the diameter of the extremity 2 in 80 the present arrangement being greater than that of the extremity 4; but this may also be varied at will.

As before indicated, the improved device is adapted for containing many primary and 85 secondary materials or substances and will serve efficiently as a retail novelty for introducing extracts, perfumery, inks, ointments, and other materials and afterward cleansed and arranged for holding salt, pepper, and 90 other condiments.

Changes in the proportions, dimensions, and minor details may be resorted to in addition to those mentioned without departing from the spirit of the invention. 95

Having thus fully described the invention, what is claimed as new is—

1. A container or receptacle, comprising a hollow body having opposite ends, one end having a central opening therein and the other foraminous, a single closing device for the central opening, and a removable cap ap-

plied over the foraminite end to primarily close the latter.

2. A container or receptacle, comprising a hollow body having one extremity dished and provided with a central opening therethrough and the opposite extremity formed with a foraminite closure, a stopper inserted in the opening of the dished extremity and a cap removably applied to the extremity having the foraminite closure to primarily seal the latter.

3. A container or receptacle of the class set forth, comprising a hollow body with an opening through one extremity and of a foraminite closure at the opposite extremity, a stopper removably mounted in the opening of the one extremity, a sealing-disk applied against the foraminite closure, and a cap removably

mounted over said disk and foraminite closure.

4. A container or receptacle, comprising a hollow body with opposite supporting extremities, one extremity having a single opening to give access to the interior of the body and the other extremity having a foraminite closure, and means for sealing either one of the extremities when the other extremity is open to dispense the contents of the body.

In testimony whereof I affix my signature in presence of two witnesses.

CHARLES F. KADE.
